UNITED STATES PATENT OFFICE.

CHARLES DE LUKACSEVICS AND CLAIR J. TERRILL, OF WEST NUTLEY, NEW JERSEY;
SAID TERRILL ASSIGNOR TO SAID DE LUKACSEVICS.

CARBURETER.

1,190,124.

Specification of Letters Patent.

Patented July 4, 1916.

Application filed July 7, 1915. Serial No. 38,619.

To all whom it may concern:

Be it known that we, CHARLES DE LUKACSEVICS and CLAIR J. TERRILL, citizens of the United States, residing at West Nutley, in the county of Essex and State of New Jersey, have invented new and useful Improvements in Carbureters, of which the following is a specification.

This invention relates to improvements in carbureters, proposing a construction of the broad or general type disclosed in our co-pending application Serial No. 29,150, and which embodies certain features of improvement over the construction shown in our said application.

The type of carbureter referred to embodies an absorbent element which is interposed between the fuel chamber and the fuel passage which is connected to the suction pipe of the engine, whereby the fuel chamber is subject to the suction set up in said passage and the fuel from said chamber is delivered into the said passage in a gaseous or vaporized form. The present invention is concerned more particularly with improvements in the construction and arrangement of the said absorbent element, in features of organization of the carbureter as a whole, in the construction and relation of the fuel and air valves, and in the relation of these valves to the absorbent element.

The objects of the invention, briefly stated, are to provide a carbureter of the type identified which shall have greater facility of assemblage, in which the renewable absorbent element shall be more durable and more readily fitted in position and shall require less attention for the purposes of cleaning, and which may be manufactured with greater facility, at less cost, and with a more advantageous arrangement of parts.

Embodiments of the invention are illustrated in the accompanying drawings, in which—

Figure 1 is a vertical longitudinal sectional view of a carbureter embodying the features of improvement aforesaid; Fig. 2 is a top plan view thereof; Fig. 3 is a detail sectional view of the absorbent element of the carbureter shown in Fig. 1; Fig. 4 is a detail vertical sectional view, partly in elevation, of a modified form of absorbent element; Fig. 5 is a detail horizontal sectional view, partly in bottom plan, of the absorbent element shown in Fig. 4; Fig. 6

is a plan view, applicable to either of the absorbent elements shown in Figs. 3 and 4; Fig. 7 is a detail elevation of the fuel and air valve of the carbureter shown in Fig. 1; Fig. 8 is a vertical longitudinal section 60 showing a modified construction of carbureter embodying the features of improvement aforesaid; Fig. 9 is a top plan view thereof; Fig. 10 is a detail vertical sectional view of the absorbent element embodied in 65 the carbureter shown in Fig. 8; and Fig. 11 is a detail top plan view of the absorbent element shown in Fig. 10.

Similar characters of reference designate corresponding parts throughout the several 70 views.

The casing of the carbureter is made, in the embodiment disclosed, of two parts, an upper part A and a lower part B. These two parts are connected together in any suitable manner, preferably by bolt fastenings C; and the part A is provided with a flange D by which the carbureter may be attached to the motor suction tube.

The parts A and B are formed to provide 80 the fuel reservoir or chamber E and the centrally arranged air and gas passage F. The part A has a centrally arranged, outwardly flaring opening G which forms an axial continuation of the passage F and in which the 85 mixture or co-mingling of the gas and air takes place or is initiated. The air and gas passage F aforesaid is defined conjointly by an open-ended cylinder or barrel 1 formed with the part B, by a fuel absorbing element 90 2 and by the flaring opening G aforesaid. In the embodiment shown in Fig. 1, the cylinder or barrel 1 also forms the inner wall of the fuel reservoir or chamber E. The cylinder or barrel 1 terminates at some 95 distance below the lower edge of the opening G and the absorbent element 2 has at its upper end a thickened portion 2^a, providing an overhanging shoulder 2^b, which said thickened portion occupies the space between the upper edge of the cylinder or barrel 1 and the lower edge of the opening G and has its inner circumferential face flush with the inner face of the cylinder or barrel 1 so as to form a portion of the annular 100 wall of the passage F. The absorbent element 2 is supported by the engagement of its shoulder 2^b upon the upper edge of the cylinder or barrel 1 and is confined or held in position by and between said cylinder 105 and the upper edge of the cylinder or barrel 1. The cylinder or barrel 1 is provided with a 110

der or barrel 1 and the part A of the carbureter casing, the said part A having an internal flat, annular facet 3 co-extensive and in contact with the upper face of the 5 absorbent element 2. The absorbent element 2 has its portion below the thickened portion 2^a of nearly or approximately the same depth as the cylinder or barrel 1, and said absorbent element, therefore, projects nearly 10 to the bottom of the fuel reservoir or chamber E and is, for the greater part of its vertical extent, immersed in the liquid fuel in said chamber or reservoir, the portion of the absorbent element 2 below the thickened 15 portion 2^a thereof being in close fitting, concentrically surrounding relation to the cylinder or barrel 1.

The part B of the carbureter casing is provided below the passage F, and in axial 20 alinement therewith, with an air chamber H arranged within a surrounding air distribution chamber I having at a suitably located point an air inlet J. Communication is established between the chambers H and 25 I by a series of relatively large openings 4 formed in the common wall *h* of the chambers H and I. The openings 4 are adjustable as to their size, preferably by means of an adjusting ring 5 surrounding and 30 closely fitting against the wall H and provided with a projecting lever portion 6. The ring 5 has openings 7 to correspond in number and form to the openings 4 which, according to the position of said ring, may 35 be moved into complete or partial register with the openings 4, or entirely out of register with said openings. The ring 5 has a circumscribing flange 8 at its lower edge which forms the base or a part of the base 40 of the chamber I.

As in the construction shown in our pending application above referred to, the carbureter includes an arrangement of valves for controlling the quantum of the fuel mixture, which said valves, the one for fuel and 45 the other for air, are so connected that the requisite proportions of air and gas will be maintained in any quantum of fuel mixture for which said valves may be adjusted.

The supply of fuel is controlled by a cylindrical valve 9 and the supply of air by a cylindrical valve 10. The valve 9 fits closely against the inner face of the passage F and the valve 10 fits closely against the 55 inner face of the wall *h*. The valve 9 is of such depth that it may completely cover the normally exposed inner face of the portion 2^a of the absorbent element 2 and the valve 10 is of such depth that it may completely 60 cover the openings 4. Fig. 1 shows the valves 9 and 10 in positions to completely cover the absorbent element portion 2^a and the openings 4. The valves 9 and 10 are connected to move as one, preferably by 65 spaced upright ribs 11, carried by the radial

arms of a spider frame which includes as a part thereof the valve 10 and which has at its center a collar 12 by which the valve unit, comprising the valves 9 and 10, is connected to the valve operating rod 13. The 70 rod 13, which is arranged co-axially of the passage F and the valve chamber H is slideable in the direction of its axis through a guiding collar 14 formed in the bottom plate of the chamber H and is operated in any 75 suitable manner, conveniently, however, by connection to an arm 15 on a rock shaft 16 journaled in a bracket 17 formed with the bottom plate of the chamber H and having a second arm 18 for connection to the lever or link, (not shown), of the valve adjusting device.

The fuel chamber or reservoir E may, if desired and as shown, be equipped with a suitable float feed mechanism, designated 80 generally as K, which, as usual, controls the admission of fuel into said chamber from a suitably constructed and arranged fuel inlet L, in this instance formed with the part B of the carbureter casing. As shown 85 in Fig. 1, the valve 9 has a vertical opening or split 9^a through which a very small portion of the surface of the part 2^a of the absorbent element 2 will be exposed, when said valve 9 is in position to otherwise 90 cover said absorbent element, for the purpose of enabling, under such condition, sufficient fuel to be supplied to the engine to maintain the operation of the engine at a very low speed, or, as it is sometimes termed, 95 "throttle speed". In this way, no adjustment of the throttle is required. The provision of the opening or split 9^a, while advantageous, is not obligatory.

Where the absorbent element is directly 100 exposed to the action of the air drawn through the passage F and is in direct contact with the valve 9, provision should be made against too free an absorption and transmission of liquid fuel by said element 105 and against undue wear thereof. These considerations can be practically satisfied in a number of different ways, three of which are herein disclosed. According to Figs. 1 and 3, the absorbent element is constructed of 110 absorbent porcelain or a hardened clay product, either of which is substantially less absorbent than ordinary felt, and both of which possess the requisite wear resisting qualities.

The absorbent element shown in Figs. 4 and 5 is, as regards external form, of the same construction as the absorbent element shown in Figs. 1 and 3, and the same reference characters are used for its designation. The absorbent element shown in Figs. 4 and 5 is, however, composed of compressed felt molded to shape and impregnated, as required, with suitable non-absorbent material, such as "bakelite" or shellac, the of- 115 120 125 130 135 140 145 150

face of which is to reduce the absorbency of the felt and to impart to the felt absorbent element the requisite stiffness or rigidity. The felt absorbent element shown in Figs. 6 and 7 has its thickened portion 2^a reinforced by a suitable metal skeleton comprising spaced vertical bars 19 arranged in an annular series and carried by and depending from a flat wear ring 20 which rests upon the upper face of the absorbent element and abuts and contacts with the facet 3 of the part A of the carbureter casing. The bars 19 are preferably of hour-glass shape in cross-section as shown, or are otherwise formed, in order that they may interlock with the felt. In this construction, only part of the surface of the thickened portion 2^a of the absorbent element is exposed to the action of the air induced through the passage F and the bars 19, coming flush with the inner face of the part 2^a of the absorbent element, take up the wear incident to the action of the valve 9. The said bars also permanently maintain the requisite form of the exposed part of the absorbent element and prevent the felt from being squeezed or deformed when inserted between the two parts of the carbureter casing. The air inlet J is preferably connected to a source of hot air supply, not shown, and may be provided, with one or more openings 21 for the admission of cold air, said openings being controlled, as to their efficient size, by a surrounding regulating ring 22.

In the construction shown in Fig. 1, the parts of the carbureter casing are, as usual, composed altogether of metal. The construction shown in Fig. 8 is generally the same, as regards the relation of the salient parts, as the construction shown in Fig. 1, but differs principally in that the body of the carbureter casing is composed of the well known insulating product usually called "bakelite" or "condensite." In this case, the "bakelite" body portion of the carbureter is formed to provide the fuel chamber or reservoir E, and the air passage F, the tubular "condensite" element defining the said air passage having an annular recess in its upper end in which is set an externally-threaded ring 23 to which are secured the metal attachment flange D' and the metal cover 24 for the fuel chamber or reservoir E. The modified construction includes the air chamber H arranged below and in alinement with the air passage F. The casing which provides the air chamber is formed of metal and is suitably attached to the "condensite" base of the fuel reservoir E. The said "condensite" base also carries the metal fuel inlet L for the fuel reservoir chamber E.

Whereas in the construction shown in Fig. 1 the absorbent element is removably fitted between the two separate parts A and B

which form the carbureter casing, in the construction shown in Fig. 8 the absorbent element, here designated as 2', is permanently incorporated in the "bakelite" inner wall of the carbureter casing. The absorbent element 2', composed of felt having "bakelite" or shellac incorporated therein, as in the construction shown in Fig. 6, is first molded to shape, and so molded, has the form shown in Figs. 10 and 11 and includes the thickened portion, here designated 2^{a'}, corresponding to the thickened portion 2^a of the absorbent element 2. The thickened portion 2^{a'} is interrupted by an annular series of radial recesses 25 and the body portion of the element 2' is preferably of bell or downwardly flaring form and is provided with suitably arranged openings 26. The cylindrical part or element which provides or defines the air passage F is composed of two companion "bakelite" parts f and f', respectively, which have complementary or mating recesses that conjointly conform to the outline of the absorbent element 2'. One of the said parts, f or f', as the case may be, has studs or pins f², and one of the said parts f or f', has ribs f³. In completing the carbureter casing, the molded absorbent element 2' is fitted between the parts f and f' in the complementary recesses provided therefor in said parts, the pins f² engaging through the openings 26 and the ribs f³ engaging in the recesses 25. Thereupon, by application of heat and pressure, the parts f and f' are molded together so that they become integrally or homogeneously connected by the pins f² and ribs f³, which said pins and ribs permanently maintain the absorbent element as a part of or incorporated in the wall of the passage F. The lower portion of the absorbent element projects below the recesses in which the element is fitted and dips into the fuel chamber or reservoir E. The upper portion of the absorbent element, i. e., the thickened portion 2^{a'} thereof, is exposed at intervals determined by the arrangement of the ribs f³ to the air induced through the passage F. In this case, the ribs f³ take up the wear of the fuel valve, here designated as 9', in the same way that this function is served by the vertical bars 19 in the construction shown in Fig. 6.

The fuel valve 9' is connected to move as one with the air valve, here designated 10', the said valves being similar in relation and operation to the valves 9 and 10 of Fig. 1 and being operated in a similar manner. In the modified construction, the special air inlet J is omitted and the air enters into the chamber H directly through the air admission openings, here designated 4' and controlled, as in the case of Fig. 1, by an apertured regulating ring, here designated 5'.

As stated in the description of Fig. 1, the

split or opening 9^a, while advantageous, is not obligatory; and in Fig. 8, the valve 9' is shown as devoid of such a split or opening. The differences between the constructions shown in Figs. 1 and 8 are concerned with structural details, the principles of operation being the same in both cases and, as in our above-mentioned pending application Serial No. 29,150, involving the delivery of the fuel in a gaseous or vaporized state into the air passage E by the absorbent element consequent to the prevailing engine suction. It will be understood that no specific description herein contained is intended to put any limitation on the scope of the appended claims which does not adhere in the language thereof.

We claim:—

1. A carbureter having a fuel chamber or reservoir and an air passage separated therefrom and having an air inlet and an outlet for connection to the motor suction tube, said chamber and said air passage being separated by an annular wall comprising a rigid body part and a relatively stiff absorbent element, the said body part having an opening communicating with the upper portion of said air passage and also communicating with the said fuel chamber, the said absorbent element occupying said opening and having an upper thickened portion which is freely exposed in said fuel chamber and which provides a shoulder for engagement upon the rigid body part of said wall, the said absorbent element having its lower portion freely exposed in said fuel chamber, and a cylindrical slide valve movable in said air passage across the freely exposed surface therein of said absorbent element.
2. A carbureter having a fuel chamber or reservoir and an air passage separated therefrom and having an air inlet and an outlet for connection to the motor suction tube, said chamber and said air passage being separated by an annular wall comprising a rigid body part and a relatively stiff absorbent element, the said body part having an opening communicating with the upper portion of said air passage and also communicating with the said fuel chamber, the said absorbent element occupying said opening and having its lower portion freely exposed in said fuel chamber and its upper portion freely exposed in said air passage, a cylindrical slide valve movable in said air passage across the freely exposed surface therein of said absorbent element, and a valve controlling the supply of air to said

air inlet, the said valves being connected to move as one and the said slide valve having a split or opening therein which always uncovers a portion of the absorbent element surface exposed in said fuel chamber.

3. A carbureter having a fuel chamber or reservoir and an air passage separated therefrom and having an outlet for connection to the motor suction tube, an air chamber arranged below said air passage and in open communication therewith, said chamber having air inlet openings in its annular wall, said fuel chamber and said air passage being separated by an annular wall comprising a rigid body part and a relatively stiff absorbent element, the said body part having an opening communicating with the upper portion of said air passage and also communicating with the said fuel chamber, the said absorbent element occupying said opening and having its lower portion freely exposed in said fuel chamber and its upper portion freely exposed in said air passage, a cylindrical slide valve movable in said air passage across the freely exposed surface therein of said absorbent element, and a second cylindrical slide valve movable in said air chamber across the air inlet openings thereof, said valves being connected to move as one.

4. A carbureter having a fuel chamber and an air passage separated therefrom and having an air inlet and an outlet for connection to the motor suction tube, the wall between the fuel chamber and the air passage comprising an annular metal part having a continuous interruption at its upper end and an annular relatively stiff absorbent element having its lower portion concentric to the said metal part and freely exposed in the fuel chamber, and having its upper portion thickened and closely fitted in the interruption of the metal part for support thereon and for free exposure in the air passage, that face of the absorbent element which is exposed in the air passage being flush with the inner face of the annular metal part, and a cylindrical slide valve movable in said air passage across the freely exposed surface therein of said absorbent element.

In testimony whereof we have hereunto set our hands in presence of two subscribing witnesses.
